CLAIM

The ornamental design for a packaging for absorbent articles, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a perspective view showing front and right sides of a packaging for absorbent articles;

FIG. 2 is a view of the right side of the package of FIG. 1;
FIG. 3 is a view of the top side of the package of FIG. 1;
FIG. 4 is a view of the left side of the package of FIG. 1;
FIG. 5 is a view of the bottom side of the package of FIG. 1;

FIG. 6 is a view of the front side of the package of FIG. 1;
and

FIG. 7 is a view of the back side of the package of FIG. 1.
FIG. 8 is a perspective view showing the front and right sides of a packaging for absorbent articles;

FIG. 9 is a view of the right side of the package of FIG. 8;
FIG. 10 is a view of the top side of the package of FIG. 8;
FIG. 11 is a view of the left side of the package of FIG. 8;
FIG. 12 is a view of the bottom side of the package of FIG. 8;

FIG. 13 is a view of the front side of the package of FIG. 8;
and

FIG. 14 is a view of the back side of the package of FIG. 8.
FIG. 15 is a perspective view showing the front and right sides of a packaging for absorbent articles;

FIG. 16 is a view of the right side of the package of FIG. 15;
FIG. 17 is a view of the top side of the package of FIG. 15;
FIG. 18 is a view of the left side of the package of FIG. 15;
FIG. 19 is a view of the bottom side of the package of FIG. 15;

(Continued)

FIG. 20 is a view of the front side of the package of FIG. 15; and
 FIG. 21 is a view of the back side of the package of FIG. 15.
 FIG. 22 is a perspective view showing the front and right sides of a packaging for absorbent articles;
 FIG. 23 is a view of the right side of the package of FIG. 22;
 FIG. 24 is a view of the top side of the package of FIG. 22;
 FIG. 25 is a view of the left side of the package of FIG. 22;
 FIG. 26 is a view of the bottom side of the package of FIG. 22;
 FIG. 27 is a view of the front side of the package of FIG. 22; and
 FIG. 28 is a view of the back side of the package of FIG. 22.
 FIG. 29 is a perspective view showing the front and right sides of a packaging for absorbent articles;
 FIG. 30 is a view of the right side of the package of FIG. 29;
 FIG. 31 is a view of the top side of the package of FIG. 29;
 FIG. 32 is a view of the left side of the package of FIG. 29;
 FIG. 33 is a view of the bottom side of the package of FIG. 29;
 FIG. 34 is a view of the front side of the package of FIG. 29; and,
 FIG. 35 is a view of the back side of the package of FIG. 29. The broken lines are shown for the purpose of illustrating parts of the article that form no part of the claimed design.
